US00D669992S

(12) **United States Design Patent**
Schafer et al.

(10) **Patent No.:** **US D669,992 S**
(45) **Date of Patent:** **** Oct. 30, 2012**

(54) **ULTRASONIC AMPLIFIER**

(75) Inventors: **Mark E. Schafer**, Lower Gwynedd, PA (US); **Adnan I. Merchant**, Fremont, CA (US); **Kristen E. Matteson**, Arvada, CO (US); **Serena Ann Chase**, Denver, CO (US); **David J. Wesley**, Lyons, CO (US); **David B. Mogill**, Westminster, CO (US); **Arjun K. Joseph**, Langhorne, PA (US); **Daniel J. Massam**, Langhorne, PA (US); **Kailyn N. Lynch**, Glenside, PA (US)

(73) Assignee: **Sound Surgical Technologies, LLC**, Louisville, CO (US)

(**) Term: **14 Years**

(21) Appl. No.: **29/362,163**

(22) Filed: **May 20, 2010**

(51) **LOC (9) Cl.** **24-01**

(52) **U.S. Cl.** **D24/170**

(58) **Field of Classification Search** D24/170, D24/144, 107, 138, 185; 330/5.5; 606/32, 606/34, 41, 42

See application file for complete search history.

(57) **CLAIM**

The ornamental design for an ultrasonic amplifier, as shown and described.

DESCRIPTION

FIG. 1 is a perspective view of an embodiment of an ultrasonic amplifier showing a new design;

FIG. 2 is a front view of the ultrasonic amplifier of FIG. 1; FIG. 3 is a rear or back view of the ultrasonic amplifier of FIG. 1;

FIG. 4 is a right side elevation view of the ultrasonic amplifier of FIG. 1;

FIG. 5 is a left side elevation view of the ultrasonic amplifier of FIG. 1;

FIG. 6 is a top view of the ultrasonic amplifier of FIG. 1; and, FIG. 7 is a bottom view of the ultrasonic amplifier of FIG. 1.

1 Claim, 4 Drawing Sheets
